Fig. 5.

Fig. 6

Fig. 7.

A schematic diagram of a mechanical assembly. It features a central vertical rod with a horizontal crossbar. A vertical rod labeled '70' is attached to the crossbar. A horizontal rod labeled '71' is attached to the vertical rod '70'. A diagonal rod labeled '72' extends from the vertical rod '70' towards the top right. A horizontal rod labeled '73' extends from the top of the vertical rod '70' towards the top left. A horizontal rod labeled '74' extends from the vertical rod '70' towards the bottom right. A horizontal rod labeled '75' extends from the top of the vertical rod '70' towards the top right. A horizontal rod labeled '76' extends from the bottom of the vertical rod '70' towards the bottom right. A horizontal rod labeled '77' extends from the bottom of the vertical rod '70' towards the bottom left.

UNITED STATES PATENT OFFICE

TUFIC N. ERBAN, OF LAWRENCE, MASSACHUSETTS

SUBMARINE AMUSEMENT DEVICE

Application filed August 14, 1930. Serial No. 475,216.

This invention relates to amusement devices of a type especially adapted for parks where people go to be entertained.

The general idea is to provide a basin or pool filled with water into which run tracks upon which a water-tight car travels.

The general idea is to provide passengers, for a small fee, with the sensation of going under water in a submarine boat but providing that they shall be fully protected against accident and that they may safely get out of the car in case anything goes wrong while it is substantially submerged.

In the preferred form of my device, the movements of the car can be controlled from a control station which overlooks the basin and from the same station an emergency outlet for the water can be opened so as to quickly empty the basin.

The propelling means for the car may be electricity, chains or ropes, or any kind of explosive, steam or compressed air engine.

When a self contained motor is used, it is usually necessary to have an attendant riding in the car but in my preferred device, everything including selling and taking tickets can be done by one man on shore.

In the drawings, Fig. 1 is a diagrammatic plan view of the entire basin, with the tracks, car and the controls.

Fig. 2 is a sectional elevation of Fig. 1 on the line 2, 2 looking in the direction of the arrows.

Fig. 3 is an enlarged diagrammatic plan view of the switch 26.

Fig. 4 is a diagrammatic elevation taken from behind the car K as it appears in Fig. 2.

Fig. 5 is a view from the rear of car K similar to what is shown in Fig. 4 but of a larger size.

Fig. 6 is a view as from the front of a car coming up to the switch 26 from the part 20 of the circuit loop, part being in section.

Fig. 7 is a detail diagrammatic plan view of the automatic mechanism for shifting the pole from one endless chain to the other.

Fig. 8 is a side elevation partly in section of a car of the electric type.

Fig. 9 is a detailed side elevation looking

up to Fig. 7 showing the two plows and their operation.

Fig. 10 is a plan view of an electric car with the hatch open.

Fig. 11 is a detail showing the application 55 of a gasoline motor as the drive mechanism.

In the drawings, A represents the ground or land upon which is built a basin B. As shown, this basin is formed by means of a wall 1 of elliptical shape. The basin has a 60 low, level part 8 in the bottom of which is an outlet 2 which can be closed by valve 3, such valve being kept closed by bolt 5 which passes through suitable straps 4 and 6. A rod or rope 16 extends from bolt 5 up to 65 a convenient place in control station C which is positioned at a high point over the basin. Rod 16 is fastened to a lever 17 pivoted at 18 so that an operator at the station C by pulling lever 17 can open the valve and let 70 the water out of the basin.

The basin slopes upward at 9 toward the control station C and preferably toward a landing stage D which may include suitable approaches 10, a gate 11 and control station C. 75

F represents the track which preferably comprises two rails and near the floor of low part 8 of the basin, forms an endless circuit loop 20, 21 which may be circular, elliptical or any other convenient shape and 80 from which extends a landing loop 22. 20 represents part of the circuit loop and 21 represents the part which completes it between the ends of the landing loop 22. The landing loop 22 extends upward on the slope 85 9 to its high point near the control station C.

In order that a car such as K can start at the landing stage D and travel down and thence ride around the circuit loop, I provide the switches 23 and 26 whereby the car can 90 be switched from one loop to the other.

As shown in detail in Fig. 3, the one switch point 26 is attached to a rod 126 attached to one arm of a bell crank lever 27 spring pressed by spring 127 in such a way that the circuit loop is normally open but can be closed when it is desired that the car K should emerge, by pulling a connecting rod 28 which extends up to the control station C. 95

The switch 23 on the other side can be 100

merely one or more freely hung points because the car coming down will move the switch itself but for safety, it is controlled in a manner similar to switch 26 with the 5 connecting rod 123 to bell crank lever 24 which is normally so pressed by spring 124 as to keep switch 23 open but can be operated by rod 25 extending up to the control station C so as to close switch 23 when desired from 10 station C.

H represents a pair of trolley wires 30, 30 supported on the inside of the basin inside the tracks as by posts 34 and brackets 35.

Trolley wires 30, 30 are connected by wires 15 31, 31 to a double pole switch 38 in the control station. From the double pole switch 38 extend the wires 32, 32 to a source of electric energy indicated by G.

The car is represented by K and should 20 be heavy enough with its passengers to stay down under water. Its bottom and sides are strictly water-proof and there are in the body on each side, the glass windows 41, 41 and inside the seats 42. The car K travels on 25 wheels 43, 43 which run on track F.

As shown, the motor 44 is positioned in the rear end of the car and may be in a compartment by itself. It is connected by wires 46, 46 with the double trolley arms 47, 47 30 of any well known type, which are carried by a bracket 147 on the upper inside of car K.

A strap 148 drives the rear wheels 43, 43 from motor 44.

48, 48 represent ventilators which extend 35 up to the roof of car K and 49 is a hatchway which opens toward the trolleys 47, 47 to protect the passengers who are coming in or going out by way of the ladder 50.

Instead of an electric motor, I can use a 40 chain and sprocket drive of a type similar to those used on roller coasters. As shown in Figs. 6, 7 and 9, this drive includes supporting sprockets 60 and 61 around which pass the chains 62 and 63 as shown in Fig. 7.

45 As shown, the line of sprockets 60, 60 with the endless chain 62 which travels around them are inside the other line of sprockets 61, 61 with their chain 63. The inner chain 62 travels around the circuit loop while the 50 outer chain 63 travels around the part 20 of the circuit loop and the part 22 of the landing loop so that when the switches 23 and 26 are moved, the car K can be driven either around the circuit or landing loop.

55 In order to shift the drive mechanism, many devices can be used either operated from inside the car or preferably so arranged with the switches 23 and 26 that when the switch is thrown, the connection 60 between the car and the drive chain is also shifted.

A device of this kind is shown in Figs. 6, 7, and 8. Either inside as shown or underneath floor 67 of a car K extending cross- 65 ways is arm 66 pivoted at 160 and having at

one end a pivoted connection for arm 69 which can be extended down through a water tight hole 169 and at its other end an arm 68 which extends down through a water tight hole 168. 70

These arms are of such length that 69 can be pushed down as shown by the dotted lines in front of a pin 65 carried by chain 63 and the end of arm 68 can be pushed down in front of a pin 64 carried by a chain 62. 75 The mechanism for operating by switch rod 126 includes two standards 74 and 75 which carry respectively the oppositely slanting plows 72 and 73 which are in such a position and so arranged that when, for instance, 80 rod 126 is pushed to the left, thus opening switch 26 to allow the car to travel around the circuit, the plow 73 is brought in front of a wheel 71 carried by arm 68 and if the car continues moving, arm 68 is brought 85 down in front of pin 64 and arm 69 is lifted clear of pin 65. See Fig. 9.

When switch rod 126 is moved to the right to switch the car onto the landing loop, the plow 72 is moved over in front of another 90 wheel 70 carried by arm 68, as shown by the dotted lines in Fig. 7 and this wheel 70 rolls up on the plow 72 thereby lifting arm 68 and depressing arm 69 until it is in front of pin 65. 95

Preferably an electric motor of any usual type is used to drive both the chains 62 and 63 and I interpose a switch such as 38 in its circuit. By locating the switch in the control station, the current can be switched off 100 and the car stopped to allow loading and unloading of passengers.

In Fig. 11, I show how an explosive gasoline line motor 91 can be used instead of an electric motor or chain drive. On account of 105 the fumes, this motor 91 should be in a compartment 90 at the rear of the car K and should be provided with an intake air pipe 92 and an exhaust air pipe 93, running up above the water level in the basin. The shaft 94 connects the motor with the rear wheels such as 95 by any suitable gearing or differential mechanism. 110

I claim:

1. In an amusement device, the combination of a basin adapted to hold water, said basin having a floor and sides together with an outlet near the floor; with a control stage near the top of one of the sides; a track near the floor forming an endless circuit loop from which an endless landing loop extends upward to a high point near the control stage; track switches between the circuit loop and the landing loop; an emergency control valve for the floor outlet; two trolley lines of wire suspended over the basin so as to be proximate the inner side of said track; a source of electric current for said trolley lines; control means extending from the control stage to each of the track switches; 125 130

means at the control stage for controlling the electric current to the trolley wires; means extending from the control stage for opening the valve in the emergency outlet; together with a passenger car which includes glass windows; wheels which rest on the track; an electric motor and connections therefrom with trolleys which travel on the trolley wires; air ventilators which project above the roof of the car, and a hatchway in the roof of the car with a door which swings upward towards the inner side of the basin.

2. In an amusement device, the combination of a basin adapted to hold water, said basin having a floor and sides; with a control stage; a track near the floor forming an endless circuit loop from which an endless landing loop extends upward to a high point near the control stage; track switches between the circuit loop and the landing loop; two trolley lines of wire suspended over the basin so as to be proximate the inner side of said track; a source of electric current for said trolley lines; control means extending from the control stage to each of the track switches; means at the control stage for controlling the electric current to the trolley wires, together with a passenger car which includes glass windows, wheels which rest on the track; an electric motor and connections therefrom with trolleys which travel on the trolley wires, air ventilators which project above the roof of the car, and a hatchway in the roof of the car with a door which swings upward towards the inner side of the basin.

3. In an amusement device, the combination of a basin adapted to hold water, said basin having a floor and sides; with a control stage; a track near the floor forming an endless circuit loop from which an endless landing loop extends upward to a high point near the control stage; track switches between the circuit loop and the landing loop; control means extending from the control stage to each of the track switches; together with a passenger car which includes glass windows, wheels which rest on the track, air ventilators which project above the roof of the car, and a hatchway in the roof of the car with a door which swings upward toward the inner side of the basin.

4. In an amusement device, the combination of a basin adapted to hold water, said basin having a floor and sides; with a control stage; a track near the floor forming an endless circuit loop from which an endless landing loop extends upward to a high point near the control stage; track switches between the circuit loop and the landing loop; control means extending from the control stage to each of the track switches; together with a passenger car which includes glass windows and wheels which rest on the track.
